UNITED STATES PATENT OFFICE.

GEORGE W. MALLORY, OF BLENHEIM, ONTARIO, CANADA.

LAMP-WICK-ADJUSTING DEVICE.

1,194,406.

Specification of Letters Patent. Patented Aug. 15, 1916.

Application filed July 1, 1915. Serial No. 37,418.

To all whom it may concern:

Be it known that I, GEORGE W. MALLORY, a subject of the King of Great Britain and Ireland, residing at Blenheim, in the Province of Ontario and Dominion of Canada, have invented certain new and useful Improvements in Lamp-Wick-Adjusting Devices, of which the following is a specification, reference being had therein to the accompanying drawings.

The invention relates to wick burners, such as are used on lamps, and having more particular reference to that type using mantles. It is essential to the proper operation that the wicks should be accurately adjusted, being neither too high nor too low, but it is difficult for the ordinary user to secure this exact adjustment. This is partly due to the fact that after lighting there is a tendency for the flame to run up as the burner increases in heat. Also the condition of the wick and the amount of carbon present alters the operation.

To overcome the difficulties as above set forth, I have devised a construction of wick-adjusting device in which the amount of movement is limited by stops. This permits of lowering the wick to turn out the light, and of raising the wick again to exactly the same position. Inasmuch, however, as the increasing carbonized portion of the wick will alter the flame, I have further provided means for compensating for this by an additional adjustment. Thus, the operator is enabled to positively set the wick in a position where it will produce the right flame, and may adjust the same to compensate for the burnt portion without the exercise of skill.

In the drawings: Figure 1 is a perspective view of a lamp burner to which my improvement is applied; Fig. 2 is a side elevation thereof; and Fig. 3 is a section on line α — α Fig. 2.

A is a lamp burner of any suitable construction, and B is the rotatable stem for raising and lowering the wick. The mechanism operated by the stem may be of any suitable construction, and illustration of the same is therefore omitted from the drawings.

C is the wheel or knob at the end of the stem B used for adjusting the same. This is preferably formed with a flange D which is internally notched or serrated as indicated at E.

F and F' are stops, preferably secured to and projecting from the burner A, and arranged to coöperate with a finger G on the stem B, so as to limit the rotary movement of the latter. The finger G is not, however, immovably attached to the stem B but is adjustable thereon, preferably by a second finger H formed integral therewith, which projects into proximity to the flange D and engages the serrations thereof. Thus, when the wheel C is turned the finger G will be moved against one or the other of the stops F and F', which will indicate the limit of movement, but if it is desired to make further adjustment the rotation of the wheel may be continued, the finger H operating as a ratchet in the serrations E.

By means of the simple construction just described, the movement of the wick may be accurately controlled. Thus, in first engaging the wick, the wheel C may be rapidly turned to raise the wick to the proper height, the finger H slipping over the serrations E. The wick is then lighted and the proper position is determined by experimentation where the flame is of the required height when the burner is fully warmed. When this adjustment is once secured the burner may be turned off and turned on as frequently as desired, and each time that it is turned on the finger G engaging the stop F' will exactly limit the height. It may also be determined by experimentation just the amount of carbonization that takes place for a definite time of burning. The operator may then adjust the wheel C in relation to the finger H one or more notches each day or each week to compensate for the carbonization. The second stop which limits the downward movement of the wick is also useful for determining the amount of trimming, so that by trimming the wick flush with the top of the burner when in its down-turned position there will be the proper amount of carbon remaining for best operation.

My improvement is exceedingly simple to manufacture, and if desired the fingers G and H may be formed from a single stamping having integral lugs I and I' which are turned over the stem B to form the securing means. The stops F and F' may be formed either by attached lugs or struck-out portions and the wheel C can also be formed as a stamping. I do not, however, limit myself to this exact construction, as it is

obvious that various modifications may be made, all of which come within the spirit of my invention.

What I claim as my invention is:—

- 5 1. The combination with a wick-adjusting stem, of a wheel on said stem for rotating the same, formed with a flange having internal serrations thereon, a member rotatably mounted on said stem having integral 20 fingers at opposite ends, one of said fingers engaging the serrations on said flange and being resilient to permit the relative rotation of the stem and the rotatably mounted member, and stops in the path of the other 25 finger for limiting the angular adjustment of said rotatably mounted member in opposite directions of rotation.
- 10 15 2. The combination with a wick-adjusting stem, of a wheel on said stem for rotating

the same, formed with a flange having internal serrations thereon, a member rotatably mounted on said stem having integral 20 fingers at opposite ends, one of said fingers engaging the serrations on said flange and being resilient to permit the relative rotation of the stem and the rotatably mounted member, and stops in the path of the other 25 finger for limiting the angular adjustment of said rotatably mounted member in opposite directions of rotation.

In testimony whereof I affix my signature in presence of two witnesses.

GEORGE W. MALLORY.

Witnesses:

Wm. J. BELKNAP,
PHYLLIS COBURN.
